BY Victor J. Evans

ATTORNEY

UNITED STATES PATENT OFFICE.

JOSEPH LORENZE, OF MORGANTOWN, WEST VIRGINIA.

EMERGENCY BRAKE.

Application filed November 3, 1926. Serial No. 146,030.

This invention relates to braking apparatus for use upon railway vehicles embodying among other characteristics means adapted for engagement with the opposed sides of the rails to prevent canting of the latter.

A further object of the invention comprehends operating means for the braking means to permit the latter to free the meeting ends of rails and to give an appreciable extent while making a turn to relieve binding action.

More specifically stated the operating means is swingingly mounted to relieve jerking of the vehicle when the device is called into use.

With the above and other objects in view, the invention further consists of the following novel features and details of construction, to be hereinafter more fully described, illustrated in the accompanying drawings, and pointed out in the appended claims.

In the drawings:

25 Figure 1 is a fragmentary side elevation of a locomotive with the present invention applied and used in conjunction therewith.

Figure 2 is an elevation of the invention per se, partly in section, to illustrate the 30 operation thereof.

Figure 3 is a sectional view taken on line 3—3 of Figure 2.

Figure 4 is a fragmentary diagrammatic plan view of a portion of the apparatus.

35 Referring to the drawings in detail, wherein like characters of reference denote corresponding parts, the reference characters 10 and 11 indicate companion plunger housings carried upon the under side of the 40 locomotive 12 by strap irons 13, substantially as illustrated in Figure 1 of the drawings. Oppositely disposed pistons 14 and 15 are carried within the housings 10 and 11 respectively. Connecting rods 16 carried by

45 each of the pistons are projected centrally of the ends of the housings and within packing glands 17 therefor to preserve compression within the housings. Links 18 depend from the outer ends of the plunger or connecting rods 16 and adapted for oscillatory and reciprocatory movement thereon. A connecting bar 19 is pivotally associated at appropriate points in the lengths of the links 18.

55 Bars 20 have the curved ends thereof correspondingly associated to the outer ends of

the connecting rods 16 and intersecting upon the opposed sides of the connecting bar 19. A pivot bolt 21 having spacing thimbles 22 carried thereby space the respective bars 60 20 upon the connecting bar 19, substantially as illustrated in Figure 3 of the drawings, to permit unrestricted operation of the links 18 and bars 20. Enlarged portions 23 are carried upon the free ends of the links 18 and bars 20 and including elongated and longitudinally disposed raceways 24, the purpose of which will be presently apparent. Brake shoes 25 forming reduced upper end portions 26 are adapted for reception within 70 the raceways 24 of the enlarged portions 23 and disposed upon the opposite sides of and in juxtaposition to the ball portions of rails.

A valve member 27 mounted within convenient reach of the locomotive engineer is 75 adapted to selectively introduce steam to either end of the respective housings 10 and 11 to operate said pistons in opposite directions.

In so doing the connecting rods 16 will be 80 drawn inwardly with the pistons and the links 18 carried thereby will swing upon the opposite ends of the connecting bar 19 to frictionally engage the shoes carried thereby with the inner sides of the aforementioned 85 portion of the rails the bars 20 will swing upon the pivot pin 21 whereby the shoes carried thereby will engage the outer sides of the rail ball.

Due to the fact that the braking apparatus operates from the piston connecting rods 16 an appreciable degree of swinging movement is permitted whereby the device when called into use will grab the rails and subsequently swing in order that the jerk as 90 experienced in rigidly mounted braking apparatus is overcome. The brake shoes as carried upon the enlarged end portions of the bars 20 are of a different configuration from that of the shoes as carried upon the 95 lower extremities of the links 18 and which are adapted to engage the outer and upper sides of rail balls in contra-distinction to the shoes as carried by the links which are adapted to engage only the inner sides thereof. When the valve member 27 is reversed steam will be introduced within the opposed 100 ends of the housings to exhaust the opposite ends thereof and to normally retain the brake shoes 25 in the positions as illustrated in 110 Figure 2 of the drawings.

The invention is susceptible of various

changes in its form, proportions and minor details of construction, and the right is herein reserved to make such changes as properly fall within the scope of the appended claims.

5 Having thus described my invention, what is claimed is:

1. A braking apparatus comprising multiple housings having oppositely disposed pistons therein, links depending from the 10 piston connecting rods, brake shoes carried upon the opposed ends thereof, a bar connecting said links to equalize the draft thereof, and additional bars carried by said piston connecting rods intersecting across the 15 first mentioned bar and terminating in juxtaposition to that of the shoes carried by the links.

2. A braking apparatus comprising multiple housings having double acting pistons 20 therein, links depending from the outer ends of the connecting rods for the pistons, brake shoes carried upon the remaining ends of the links, a connecting rod cooperatively associating the links, bar members intersecting 25 upon the opposed sides of the connecting bar and providing curved end portions correspondingly associated with the respective ends of said connecting rods, and a pivot pin carried by the connecting rod and swingingly mounting the last mentioned bars 30 thereon.

3. A braking apparatus comprising multiple housings having double acting pistons therein, links depending from the outer ends 35 of the connecting rods for the pistons, brake shoes carried upon the remaining ends of the links, a connecting rod cooperatively associating the links, bar members intersecting

upon the opposed sides of the connecting bar and providing curved end portions correspondingly associated with the respective ends of said connecting rods, a pivot pin carried by the connecting rod and swingingly mounting the last mentioned bars 45 thereon, and brake shoes carried upon the opposed ends of the bars.

4. A braking apparatus for use upon railway vehicles comprising multiple housings having double acting pistons therein, links depending from the outer ends of piston connecting rods, a connecting rod cooperatively associating said links, bar members intersecting across the opposed faces of the connecting rod and terminating in curved end portions correspondingly associated with the 50 adjacent ends with the piston connecting rods, a pivot pin carried by the connecting rod mounting said bars for swinging movement thereon, and brake shoes carried upon the remaining extremities of the links and 55 bars for active engagement with rail balls when said pistons are called into active use.

5. A braking apparatus comprising multiple housings having pistons therein, links connected with the pistons, brake shoes carried by the links, a bar connecting the links to equalize the draft upon the shoes, additional bars pivotally connected at their intersections with the bar and similarly connected 60 with the piston connected ends of the links, and brake shoes carried upon the opposed ends of the additional bars being disposed in opposed relation to the first mentioned shoes.

In testimony whereof he affixes signature.

JOSEPH LORENZE.
